(57) **CLAIM**

The ornamental design for a helmet mounted visor, as shown and described.

DESCRIPTION

FIG. 1 is a front perspective view of a helmet mounted visor in accordance with my new design;

FIG. 2 is a front elevational view of the helmet mounted visor shown in FIG. 1;

FIG. 3 is a rear elevational view of the helmet mounted visor shown in FIG. 1

FIG. 4 is a left-side elevational view of the helmet mounted visor shown in FIG. 1;

FIG. 5 is a right-side elevational view of the helmet mounted visor shown in FIG. 1;

FIG. 6 is a top plan view of the helmet mounted visor shown in FIG. 1; and,

FIG. 7 is a bottom plan view of the helmet mounted visor shown in FIG. 1.

The broken lines shown in the drawings represent portions of the helmet mounted visor that form no part of the claimed design.
